No. 761,811.

PATENTED JUNE 7, 1904.

N. L. ANDERSON.

TYPE WRITER.

APPLICATION FILED MAR. 2, 1903.

NO MODEL.

UNITED STATES PATENT OFFICE.

NEAL LARKIN ANDERSON, OF MONTGOMERY, ALABAMA.

TYPE-WRITER.

SPECIFICATION forming part of Letters Patent No. 761,811, dated June 7, 1904.

Original application filed May 10, 1902, Serial No. 106,802. Divided and this application filed March 2, 1903. Serial No. 145,712.
(No model.)

To all whom it may concern:

Be it known that I, NEAL LARKIN ANDERSON, a citizen of the United States, residing at and whose post-office address is 300 Washington street, in the city of Montgomery, county of Montgomery, State of Alabama, have invented certain new and useful Improvements in Type-Writers; and I do hereby declare the following to be a full, clear, and exact description of the invention, such as will enable others skilled in the art to which it appertains to make and use the same.

My invention relates to certain automatic line-spacing and paragraphing mechanism for type-writers, described in my application filed May 10, 1902, Serial No. 106,802, for improvements in type-writers, of which the present application is a division.

The invention is illustrated in the accompanying drawings, in which—

Figure 1 is a view of the left-hand end of a type-writer, showing the automatic line-spacing and paragraphing mechanism applied thereto. Fig. 2 is a front elevation of the same. Fig. 3 is a view corresponding to Fig. 1 with the line-spacing mechanism thrown out of operation. Fig. 4 is a front elevation corresponding to Fig. 2, showing the operation of the line-spacing and paragraphing mechanism when the carriage is returned by means of the paragraphing-lever. Fig. 5 is a fragmentary view showing the relation of the spacing mechanism after the carriage has been returned to the beginning of a line with-out spacing. Fig. 6 is a front view of the same. Fig. 7 is a detail view of the paragraphing-lever. Fig. 8 is a view corresponding to Figs. 2 and 4, showing the relation of the parts of the automatic spacing and paragraphing mechanism when the carriage has been returned to the starting-point by the usual means employed for that purpose.

Referring to the drawings, R and R' indicate, respectively, the rotary platen and the reciprocating paper-carriage of a standard type-writing machine constructed and operating upon principles well known to those skilled in the art.

It is the purpose of my invention, without in any manner changing or varying the regular means applied to such machines for returning the carriage to its starting-point and for rotating the platen to feed the paper and space the lines of writing, to provide independent mechanism which will be operated by the return movement of the carriage, to rotate the platen to properly space a new line, and, furthermore, to provide, in conjunction with said last-named mechanism, mechanism for stopping the carriage at a predetermined point in its return when it is desired to begin a paragraph.

To the left end of the platen-cylinder R is secured a crown-ratchet R², which is engaged on its peripheral face toward the rear of the machine by a spring-pawl Z¹, slidably mounted in a socket-support Z⁴, secured to the end of a lever Z. The lever is journaled in a block or support L, which is secured to the paper-carriage by brackets L³ and L⁴, said lever having a downward extension overhanging the front edge of the machine. A spiral spring Z⁷, secured at one end to the lever Z and at the other end to the journal-block L, tends to hold the lever Z in such position that the depending arm thereof is substantially vertical and pawl Z⁶ is in position to engage the teeth of ratchet R², and said spring serves to return the lever to the position aforesaid whenever said lever is released from any agency that moved it from its normal position.

Mounted in brackets N N' on the front standards of the machine-frame and capable of partial rotation therein is a rod, B, upon which is adjustably secured a stop mechanism comprising a sleeve B⁵, secured to the rod by a set-screw B⁷, from which sleeve projects a lug B⁸, having an angular extension-rod B⁹, generally parallel with rod B. A spiral spring B⁴, secured at its respective ends to the machine-frame and rod B, serves to turn the latter, so that the stop-lug B⁸ and the extension-rod B⁹ lie in a substantially horizontal plane and in the path of the lower end of lever Z. Secured to the rod B, at the right-hand end thereof, is a curved lever-arm Q, by means of

which the rod B is rotated in the bearings N' and stop-lug B⁸ is turned down out of the path of lever Z, as shown in Figs. 3 and 4.

The mechanism above described constitutes 5 the automatic line-spacing mechanism and operates as follows: As the carriage approaches the end of a line lever Z occupies the position indicated in Figs. 1 and 2, with pawl Z⁶ ready to engage one of the normal faces of the 10 ratchet-teeth. Ordinarily the carriage is returned to the starting-point by grasping a lever projecting from the carriage and drawing the latter to the right. The operation, which is usually a manual one, may of course 15 be accomplished by any automatic carriage-return mechanism. As the carriage approaches the end of its return movement the lower end of lever Z strikes lug B⁸, and the continued movement of the carriage rocks said lever in 20 the bearing-block L and forces pawl Z⁶ into engagement with the ratchet, thereby turning the platen R a distance equal to the throw of the pawl. As the carriage is advanced during the writing operation lever Z is re- 25 tracted from engagement with stop-lug B⁸ and under the influence of spring Z⁸ assumes a vertical position and causes spring-pawl Z⁶ to ride over the inclined faces of the teeth of ratchet R² into position for a subsequent spacing 30 operation on said platen. By adjusting the position of the stop-lug B⁸ the extent of movement of the platen may be regulated. It is of course understood that the extent of movement of the platen for spacing different 35 widths of lines can also be regulated by the usual platen ratchet-stops, such as are used on all standard machines. It is sometimes desirable, however, to return the carriage to the beginning of a line without spacing—as, for 40 example, for the purpose of correcting an error in the line previously written. In order to accomplish this, the operator depresses lever-arm Q, thereby turning rod B in bearings N N' and throwing the stop-lug B⁸ out of 45 the path of movement of the spacing-lever Z. When the carriage is returned, the said lever Z rides over the stop-lug B⁸ aforesaid, so that there is no spacing movement of the platen. If the lever Q be now released, spring B⁴ 50 turns the rod B and forces extension-arm B⁶ of the stop-lug B⁸ against the lower portion of lever Z, and when the carriage carries said lever out of contact with said arm B⁶ the latter together with lug B⁸ and rod B are turned 55 up into horizontal position to continue the spacing operation upon the next return of the carriage. It will be noted that the extension-rod B⁶ serves the double function of preventing the lever-arm Z from passing behind 60 the stop-lug B⁸, and thus stopping the advance of the carriage, and also incidentally to hold down the rod B until the lever Z has passed beyond the lug B⁸ in advance of the carriage, as shown in Figs. 5 and 6.

When it is desired to start a new paragraph, 65 the operator usually returns the carriage to the beginning of the line and operates the spacer until the point of beginning the paragraph is reached. In order to obviate this time-consuming and care-exacting operation, 70 I have provided an additional lever attachment to the automatic line-spacing lever, by means of which the carriage may be returned by hand and automatically stopped at any predetermined point to begin a paragraph. 75 This paragraphing device comprises an upwardly-extending lever-arm Z², loosely journaled upon the horizontal portion of lever Z, having a depending projection Z³ on the lower side thereof, and a laterally-extending pin Z⁴, 80 adapted to engage an upwardly-extending pin Z⁹ and said lever Z, said pin Z⁹ lying on the opposite side of said pin Z⁴ from the platen end. A horizontal rod J, secured to the upper side of the machine-frame by means of 85 a bracket J¹ and set-screw J², bears upon its outer end an adjustable stop-lug J', which is secured in position by a set-screw J³, which lug rises in the path of movement of the depending lug Z³ on lever Z². 90

When the carriage is returned, either manually or mechanically in the ordinary way, the lug Z³, owing to its lateral disposition on the lower side of the lever Z², does not engage the stop-lug J'. Hence the carriage returns the 95 full distance to the starting-point. When it is desired to stop the carriage in its return movement at an appropriate point to start a new paragraph, the stop lug or detent J' is set at an appropriate point on the rod J, determined by the scale marked thereon, and the lever Z² is grasped by the hand and the carriage returned by this means. As said lever Z² is engaged it is rocked to the right, so that pin Z⁴ engages pin Z⁹ on the line-spacing lever Z, causing the latter to operate the platen to feed the paper for a new line. As the carriage continues its return movement lug Z³, which is now thrown directly in the path of the stop-lug J', engages the latter 105 and arrests the movement of the carriage at the appropriate paragraphing-point, as indicated in Fig. 4. It is to be particularly noted that this latter operation only takes place when the carriage is returned by means of 110 lever Z². At all other times said lever, which is loose upon the rod Z, does not turn as the latter is oscillated. Therefore lug Z³ is kept 115 out of the path of the stop-lug J'. 120

Having thus described my invention, what I claim is—

1. A type-writing machine, having a paper-carriage, a spacing-lever operated to turn the platen by the return of the carriage, an auxiliary paragraphing-lever loosely mounted upon said spacing-lever, and adapted to return the carriage and co-operating lugs on the last-mentioned lever and the machine-frame to 125

stop the carriage at a predetermined point in its return movement, when the carriage is moved by said paragraphing-lever.

2. A type-writing machine, having a paper-carriage, a spacing-lever operated to turn the platen by the return of the carriage, and an auxiliary paragraph-lever connected with the spacing-lever operating to stop the carriage at a predetermined point in its return movement 10 and to actuate the spacing-lever, when the carriage is returned by said paragraphing-lever.

3. A type-writing machine, having a paper-carriage, a spacing-lever operated to turn the platen by the return of the carriage, and an auxiliary mechanism adapted to stop the carriage automatically at a predetermined point for the purpose of paragraphing, said mechanism consisting of a hand-lever loosely journaled on said spacing-lever, a pin on said paragraphing-lever engaging a similar pin on said spacing-lever to space the platen when the carriage is returned, a lug or projection on said paragraph-lever, and a lug on the machine-frame adapted to engage said projection on the paragraph-lever, and stop the carriage at a predetermined point of its return movement, when said movement is effected by means of said paragraph-lever.

30 4. A type-writing machine, comprising a paper-carriage, means for normally returning said carriage to its initial point, and a paragraphing mechanism adapted to stop said carriage at a predetermined paragraph-point, said mechanism comprising a hand-lever pivoted to the carriage and having a lug or projection thereon, and a lug or stop on the machine-frame adapted to engage the projection on said lever when the carriage is returned by 40 said hand-lever.

5. A type-writing machine, comprising a paper-carriage, means for normally returning said carriage to its initial point, and a paragraphing mechanism, said paragraphing mechanism consisting of coöperating parts normally out of operative relationship, and means for momentarily throwing them into operative relationship at a predetermined paragraph-point and thereupon automatically 45 reëstablishing their non-operating relationship, said means comprising a hand-lever on the carriage for returning the latter to the beginning of a new paragraph.

6. A type-writing machine, comprising a

paper-carriage, means for normally returning 55 said carriage to its initial point, and a paragraphing mechanism, said paragraphing mechanism consisting of coöperating parts normally out of operative relationship, and means for momentarily throwing them into 60 operative relationship at a predetermined paragraph-point and thereupon automatically reëstablishing their non-operating relationship, the shiftable or setting element of said paragraphing mechanism being mounted on 65 the carriage and comprising a pivoted hand-lever for returning the carriage to the beginning of a new paragraph.

7. A paragraphing-stop for type-writing machines, adapted to limit the return movement thereof at will comprising an adjustable and a fixed stop member respectively attached to the carriage and to a relatively stationary part of the machine, means for holding said members normally out of contacting position 70 during the ordinary sliding movements of the carriage in either direction, and means comprising a hand-lever for returning the carriage to the beginning of a new paragraph whereby the stop members may be caused to contact 75 during the return movement of the carriage and arrest such movement thereof at any desired point.

8. A paragraphing-stop for limiting the return movement of the carriage of a type-writing machine, comprising a swinging member attached to the carriage and a member attached to a relatively stationary part of the machine, one of said members being laterally adjustable to regulate the point at which the 80 carriage will be arrested by the stops, spring-actuated means for swinging one member normally out of contacting position with the other, and means comprising a hand-lever for returning the carriage to the beginning of a 85 new paragraph whereby said spring-actuated member may be thrown into engaging position by the hand of the operator simultaneously with or during the return movement of the carriage so that said stops will arrest such 90 movement of the carriage at any predetermined point.

In testimony whereof I affix my signature in presence of two witnesses.
